UNITED STATES PATENT OFFICE

CHARLES A. TOSI, OF RIDGEWOOD, NEW JERSEY, ASSIGNOR TO P. PASTENE & CO., INC.,
OF BOSTON, MASSACHUSETTS

DESIGN FOR A BOTTLE

Application filed May 30, 1930. Serial No. 35,858. Term of patent 7 years.

To all whom it may concern:

Be it known that I, CHARLES A. Tosi, a citizen of the United States of America, residing at Ridgewood, in the county of Bergen and State of New Jersey, have invented a certain new, original, and ornamental Design for a Bottle, of which the following is a specification, reference being had to the accompanying drawing, forming a part thereof.

Fig. 1 is a front view of a bottle embodying my new design.

Fig. 2 is a side view thereof.

Fig. 3 is a sectional view on line 3—3.

I claim:

The ornamental design for a bottle, as shown.

In testimony whereof I affix my signature.

CHARLES A. TOSI.
